UNITED STATES PATENT OFFICE

2,287,151

CALCULATING MACHINE

Joseph A. V. Turck, Wilmette, Ill., assignor to
 Felt & Tarrant Mfg. Co., Chicago, Ill., a corpora-
 tion of Illinois

Application September 21, 1940, Serial No. 357,678

21 Claims. (Cl. 235—82)

This invention relates in general to calculating machines, and more particularly to the provision of means for facilitating the use of power-driven, key-responsive machines in subtractive operations.

In calculating machines of the type shown in my prior United States Letters Patent No. 2,063,962, issued December 15, 1936, and in other machines having actuating mechanism adapted to drive the registering or accumulating mechanism in only one direction, subtraction is performed by a process of complementary addition. For example, if it is desired to subtract "127" from the number "824," the latter is registered in the numeral wheels of the accumulator, and the nine's complement of the subtrahend less one, or the ten's complement of the units order and the nine's complement of all other orders of the subtrahend, namely, "873," is added to the minuend. This would normally leave a result of "1697" in the accumulator. In certain of the prior art machines, such as those disclosed in the patents to D. E. Felt No. 767,107 and No. 960,528, issued on August 9, 1904, and June 7, 1910, respectively, a subtraction or carry cut-out lever is provided in association with each denominational order or accumulator mechanism, except the units order, which is selectively operable to prevent a transfer or a carry of the tens thereto. In this manner, the tens added to the left of the highest order of the minuend in subtractive operations performed by complementary addition are eliminated. These subtraction levers are manually operable, and must be held in operative position in order to prevent a transfer to the associated order of accumulator mechanism. In performing the above problem on such a machine, by actuating the subtraction lever in that order to the left of the first figure of the subtrahend and manually retaining the same in operative position, the carrying of the tens to such order of the accumulator is prevented, and the correct result, "697," will appear on the numeral wheels of the accumulator.

In the instant invention, however, the operator is relieved of the responsibility and effort of selecting and holding the proper subtraction lever in operative position while performing the subtractive operation. This is accomplished by means of a subtraction control key operative to condition the machine to automatically add "9's" in all columns to the left of that in which an adding or digital key is first depressed after the depression of said control key. The subtraction levers of the prior patents referred to are elimi-

nated, and the resulting carry is allowed to take place. In the problem above referred to, this carry will leave the figure "1" in the column to the left of that in which the first figure of the complement of the subtrahend has been added, and to eliminate it, and bring the numeral wheel to zero, "9" is automatically added. This results in a carry to the numeral wheel in the next column to the left, so it will be readily seen that it is necessary to add "9's" in all columns to the left of that in which the first figure of the subtrahend occurs, in order to bring all of the higher denominational wheels to zero position.

A principal object of the instant invention, therefore, is the elimination of the individual columnar subtraction or carry cut-out levers heretofore used in calculating machines, and the provision of a subtraction control key, depression of which conditions the machine for automatic subtraction.

Another important object of the invention is the provision of means which relieve the operator of the necessity and responsibility of selecting and holding the proper subtraction or carry cut-out lever in operative position while performing a subtractive operation.

A further important object of the invention is the provision of means for conditioning a calculating machine for automatic subtraction, whereby subsequent operation of the digital key representing the first or left hand figure of the subtrahend will cause "9's" to be automatically added in all denominational orders of the accumulator to the left of that of the operated key.

Another important object of the invention is the provision in such a machine of means for maintaining the subtraction control key in operative position, and for automatically releasing it in response to the depression of any digital key of the denominational order of keys.

Another important object of the invention is the provision of means for automatically resetting the machine for additive actuation, after a subtractive operation has been accomplished.

Numerous other subjects and advantages of the invention will be apparent as it is better understood from the following description, which, when taken in connection with the accompanying drawings, discloses a preferred embodiment thereof.

In the drawings,

Figure 1 is a top plan view, broken away centrally from front to back, of a calculating machine embodying my invention showing the "add"

and "subtract" keys located to the left of the several denominational orders of digital keys;

Figure 2 is a longitudinal, vertical section taken through the calculating machine shown in Fig. 1, to the left of the "add" and "subtract" keys, showing certain details of the mechanism for conditioning the machine for subtraction;

Figure 3 is a longitudinal, vertical section taken through the calculating machine shown in Fig. 1, on a plane adjacent a column of digital keys;

Figure 4 is an enlarged, transverse section taken at the rear of the machine with certain parts omitted to show the details of the subtraction control mechanism;

Figure 5 is a fragmentary elevational view of the automatic subtraction control setting mechanism in subtractive position, as distinguished from the additive position illustrated in Fig. 2; and

Figures 6, 7, 8 and 9 are enlarged, detail views of the subtraction control mechanism in various stages of operation.

Figure 10 is a fragmentary elevational view of the overflow column carry cut-out lever at the instant of performing the function of latching the carry transfer pawl in inoperative position.

For the purpose of illustrating my invention, I have shown in the drawings a key-responsive, power-driven calculating machine similar to that shown and described in Patent No. 2,063,962, hereinbefore referred to. Referring more particularly to the drawings, the calculating machine is shown as having an outer casing 21 within which the various instrumentalities of the machine are mounted on skeleton frame members or partition plates 22 disposed between the actuating mechanisms of the several denominational orders and secured together in spaced relationship at suitable points by tie-rods 23. A plurality of columns of digital keys 24 are arranged to extend through a keyboard 25, positioned as part of the upper wall of the casing 21, which keys are adapted for manipulation to determine the digital degree of actuation to be imparted to the different denominational orders of accumulator mechanism. Each column of keys 24 controls the rotation of an accumulator actuating pinion 26 (Fig. 3) journaled upon a transverse shaft 27 that extends across the machine and is supported by the frame members 22. Rotation of each of the actuating pinions 26 is transmitted through an internal ratchet mechanism to a combined lantern wheel and accumulator gear 28 (Figs. 2 and 3) which is also journaled on the shaft 27. The gear of the lantern wheel 28 meshes with a carrying gear (not shown) journaled on a shaft 29 (Fig. 2), which is disposed in parallel relationship to the shaft 27. The carrying gear also meshes with an intermediate gear 31 journaled on a transverse shaft 32, which in turn meshes with a numeral wheel pinion 33 journaled on a transverse shaft 34 and fixed to a numeral wheel 35.

Carrying mechanism is provided in each denominational order of the accumulator mechanism for the purpose of imparting a digital unit of actuation thereto each time that a tens transfer is to take place from the next lower denominational order of the accumulator. This mechanism, as well as that hereinbefore described, is more fully disclosed in United States Letters Patent No. 1,357,747 and No. 1,357,748, issued on November 2, 1920, and includes a carrying-cam member 36 (Fig. 2), which is given a 180° rotation by a suitable carrying motor spring 37 asso-

ciated with a carrying gear of the next lower denominational order for each tens transfer that is to be effected. The carrying-cam member 36 acts upon a dolly roll 38 secured to a bell crank carrying-lever 39 to swing the latter in a clockwise direction, viewing Fig. 2. Such swinging of the carrying-lever 39 causes a carrying pawl 41 pivotally mounted on said lever to throw the lantern wheel and accumulator gear 28 a sufficient distance to impart, through the train of gears, a digital unit of actuation to the numeral wheel 35.

The adding is accomplished upon depression of the keys 24 and corresponding actuation of rack sectors 42 (Fig. 3) which are in mesh with the pinions 26, a said sector being associated with each denominational section of the accumulator unit in association with its controlling column of keys. The rack sectors and the control and actuating mechanism for them are duplicated for each denominational order of the calculating machine, and a general description of a single set of such mechanism will be sufficient for an understanding of them all, except that they have to be arranged and adapted to cooperate selectively and collectively with the power members.

The rack sectors 42 are mounted upon a shaft 43 which extends through the partition plates 22 of the machine, and are adapted to be moved downwardly (viewing Fig. 3) on an idle or setting stroke in amount determined by the value of the particular digital key 24 of the associated column depressed, this amount increasing in graduating steps from one to nine. The keys 24 in addition act through a power trip mechanism to effect a connection whereby power supplied by an electric motor, indicated generally at 44 (Fig. 3), through a power shaft 45, which is connected to the motor in any suitable manner, is effective to extend a spring 46 associated with the particular order of mechanism with which the key depressed is identified. Release of this spring thereafter accomplishes adding movement in amount determined by the particular digital key of the order depressed. Upon depression of said key, the rack segment 42 is moved through its idle or downward stroke by the power shaft 45 into position to impart proper and accurate digital accumulation to the adding mechanism upon its return movement, which is accomplished by the associated spring 46.

In the calculating machine shown in the drawings, depression of a key 24 causes its stem 47 (Fig. 3) to engage a parallel motion bar 48 which is pivoted at the front at 49 and at the rear at 51 to levers 52 and 53, which levers are pivoted in turn upon cross shafts or rods 54 extending through the partition plates 22. A link 55 is pivotally connected at 56 to the lever 52 and at 57 to the lever 53. The bar 48, levers 52 and 53 and the link 55 form part of a parallel motion device, and are constructed and mounted as shown and described in United States Letters Patent No. 2,063,962, earlier mentioned. Further and more particular description of these parts is therefore thought to be unnecessary. Each of the rack sectors 42, as stated above, is pivoted upon a cross shaft 43, and is respectively connected to a hook 58 by a link 59 (the hook 58 and link 59 being pivotally connected to a vertical guide member 60), and to a movement controlling bar 61 by a link 62 (Fig. 3), the former said connection being through a compensating device 63. The operation of the parts is such

that upon depression of a key 24, the stem 47 engages and depresses the bar 48, imparting motion to the parallel motion device, and through suitable control mechanism which it is thought need not be described herein in detail, but which includes a dog 84 pivoted on the bar 48, moving the hook 58 down into engagement with a toothed wheel 65 which is fastened to the power shaft 45. The engagement of the hook 58 with the wheel 65 pulls the link 59 toward the rear of the machine, or toward the left, viewing Fig. 3, which imparts downward motion to rack sector 42 and link 62 through the compensating device 63. Forward motion is thus imparted to the digital control bar 61, until one of several lugs projecting laterally therefrom is stopped by the stem 47 of the key 24 depressed.

The link 59 extends the spring 46, which is connected at its rear end to the guide member 60 and at its forward end to a partition plate 22, and moves the rack sector 42 downwardly on an idle stroke and into position to impart an adding movement upon release of the hook 58 and contraction of the spring. The downward movement of the rack sector 42 is under the control of the digital control bar 61, and the rack sector is halted when it has been moved downwardly the proper distance, enabling it upon return to impart the degree of digital advancement to the adding mechanism which corresponds to the particular key depressed. The compensating device 63 permits the continuation of the rearward movement of the link 59 after downward movement of the rack sector 42 has been stopped, and until the end of the power stroke and the automatic release of the hook 58. The release of the hook 58 is accomplished automatically in each instance, after a set increment of action has been imparted to the link 59, by the teeth of the wheel 65. Upon the return stroke (the operative stroke of the rack sector), the compensating device 63 permits movement of the parts in reverse direction to the beginning of the adding movement and thereafter the adding actuation is accomplished.

It is apparent, therefore, that upon depression of a key 24, the digital control bar 61 determines the degree and extent of the downward movement of the rack sector 42, and the bar 48 effects connection of the latter to the power mechanism. In this operation, the key 24 which has been operated is held depressed until release of the hook 58 from the wheel 65, when the key will be released and returned to normal raised position. It will be understood that, while no two keys 24 of the same column or denominational order may be operated simultaneously, any key of one order may be operated at the same time as any desired key of any other denominational order or orders.

Having in mind the general construction and arrangement of the machine elements above described, the novel subtraction control mechanism provided by the present invention will now be described. In general the invention contemplates the provision of mechanism for each denominational order of the machine conditioned for operation by the nonselective actuation of a subtraction control device such as a key and operated selectively after such conditioning as an incident to the registration of the first or left hand figure of the subtrahend for preventing any apparent change in the setting of the accumulators and associated numeral wheels in orders higher than said first figure.

More specifically, the invention contemplates the provision of mechanism for automatically adding "9's" across the machine in all columns to the left of that in which the first key is depressed in entering the subtrahend, for the purpose already mentioned. This is accomplished by utilizing the power derived from the power action, in response to the depression of a digital key 24 in any denominational order to actuate through a suitable power transmitting connection, the power trip mechanism in the next higher denominational order. The means for establishing the connection is conditioned for operation by the subtraction control device and operated in response to the depression of the digital key 24. In the exemplary embodiment a power transmitting connection is established between the actuating mechanism of one order and the parallel bar device of the next higher order to cause the hook 58 in the latter order to be engaged with its associated toothed wheel 65, thus imparting downward motion to the rack sector 42 controlled thereby and subsequent accumulative actuation upon its upstroke. As no key has been depressed in said next higher denominational order during such action, the digital control bar 61 therein will receive a full throw, with a consequent maximum downward movement of the associated rack sector 42 sufficient to add "9" into such order of the accumulator upon its upstroke. This action of adding "9's" is, of course, repeated in all columns to the left of that in which a key 24 is first depressed.

The subtraction control device in its preferred form comprises a set of keys including "add" and "subtract" control keys 71 and 72, respectively, (Figs. 1, 2 and 5) located to the left of the ordinal series of keys 24 for convenient access. The keys are provided with the usual stems 73 extending through the keyboard 25 and pivotally secured in any suitable manner to the opposite ends of a walking-beam lever 74, journaled on a short transverse shaft 75. Pivotally secured to the lower end of the walking-beam lever 74 is one end of a connecting link 76, the opposite end of which is pivoted to a centering plate or disk 77 securely fixed to a transverse shaft 78 extending transversely across the several denominational orders of the machine. It will be apparent that depression of either of the keys 71 or 72 by means of the walking-beam lever 74, link 76 and plate 77 will rock the shaft 78. The shaft 78 is resiliently maintained in either position to which it is so rocked (Figs. 2 and 5) by means of an arm 79 which is journaled on a stub shaft 81 and is provided with a centering stud 82 adapted to engage either one of a pair of notches 83 provided in the edge of the centering disk 77. The arm 79 is resiliently maintained in engagement with one of the notches 83 by means of a spring 84, until it is moved out of engagement therewith by depression of key 71 or key 72.

Provided in association with each denominational column or order of digital keys 24 are a pair of upper and lower lugs 85 and 86, respectively, which are rigidly secured in any suitable manner to the shaft 78 (Figs. 4 and 6 to 9). The shaft 78 and lugs 85 and 86 are normally maintained in their positions of Figs. 6 and 8 by the stud 82 of arm 79 engaging the lowermost notch 83 in plate 77, such parts normally being in their positions of Fig. 2, with the "add" key 71 depressed. In such normal position, each lug 86

is in engagement with the forward end of a horizontal arm 87 pivotally mounted at 88 on one upstanding arm of a substantially U-shaped lever, which is indicated generally by reference numeral 88 and is journaled on a transverse shaft 81. The rear end of each arm 87 is connected to one end of a coil spring 82, the other end of which is connected to the transverse portion of the lever 88. Upon depression of the subtraction control key 72, and consequent rocking of the shaft 78 in a clockwise direction, viewing Fig. 6, the lugs 86 are moved out of engagement with their associated arms 87, allowing the latter to rise under tension of springs 92 into contact with shaft 78, as shown in Fig. 7. In its raised position, a shoulder 83 on each arm 87 is disposed in the path of a horizontal lip 94 formed on the lower end of a vertical lever 95 pivoted on a transverse shaft 96 and provided with a slightly offset, bifurcated upper end 97 adapted to embrace a stud 88 secured to the associated link 55. As has been earlier described herein, upon depression of a key 24, link 55 is moved to the right, viewing Figs. 3 and 6, thereby causing vertical lever 95 to swing clockwise on its pivot 96, causing its lower, bent end 94 to contact shoulder 83 on arm 87 and lock lever 89 in a counter-clockwise direction to its operative position of Fig. 7.

Each lever 89 is provided with an upstanding arm 99, opposite that pivotally secured to the arm 87, which has a lateral extension 101 in engagement with the lower end of a depending latch 102, journaled on shaft 96. Upon rocking lever 89 from its position of Figs. 6 and 8 to its position on Figs. 7 and 9, a shoulder 103 on the latch 102 is urged out of engagement with a lateral shelf 104 formed on a double-hooked latch 105 which is pivotally mounted at 106 (Figs. 8 and 9) on the lower end of a vertical lever 107, also journaled on shaft 96. The latch 102 is normally maintained in its forward position of Fig. 8, where it engages with the shelf 104 on lever 105, by a spring 108 (Figs. 4 and 9), but upon being urged rearwardly by arm 99, it allows the rearward portion of the double-hooked latch 105 to rise to its position of Fig. 9 under tension of a spring 109, one end of which engages an upright portion 111 of the double-hooked latch 105, while the opposite end is retained by a lug 112 (Fig. 3) formed on the adjacent intermediate frame member 22. Thus, a hook 113 formed on the rearward portion of latch 105 engages a pin 114 secured to an arm of the associated vertical guide member 60 which is pivotally connected to the hook 58 and link 59, as has been previously described, and is pivotally mounted at its lower end on a transverse shaft 115. An arm 116 formed on the lever 107 normally rests against a stud 117 secured to the adjacent intermediate frame member 22 to limit counter-clockwise movement of lever 107 under tension of spring 109, viewing Figs. 8 and 9.

As has been earlier described, upon depression of a digital key 24, hook member 58 is allowed to drop into the path of the teeth of the power drive wheel 65 and be moved thereby toward the rear of the machine, or to the left (viewing Fig. 3). Simultaneously, the guide member 60, which, together with hook member 58, is pivotally secured to the link 59, is swung to the left (viewing Figs. 3 and 9) on its pivot 115, carrying with it the double-hooked latch 105, due to engagement of hook 113 with the pin 114 secured to the guide member. Such rearward movement of hook 113

of the double-hooked latch 105 swings its associated lever 107 clockwise on its pivot 96 from its conditioned position of Fig. 9. Viewing Figs. 4, 8 and 9, it will be noted that vertical lever 101 is provided at its upper end with an offset arm 118 in engagement with the stud 88 on the link 55 of the next higher denominational order. As the lever 107 is thus swung clockwise on its pivot, the arm 118 urges the link 55 forwardly, or to the right viewing Figs. 3 and 9. Thus power from the actuating mechanism of one denominational order is transmitted through the connection provided by the hooked latch 105 and lever 107 to the power trip mechanism of the next higher denominational order.

Movement of the link 55 imparts motion to the parallel motion device which controls depression of the hook 58 into the path of its associated toothed wheel 65, which results in an adding actuation. Movement of the parallel motion device not having resulted from depression of a key 24 in such higher order, it will be readily apparent that bar 61 which controls the digital setting of the rack sector 42 will receive full forward movement, with a consequent maximum downward movement of the rack sector sufficient to add "9" into the accumulator upon the up-stroke of the sector under tension of spring 46.

Such rearward movement of the double-hooked latch 105 is also utilized to reset shaft 78 to its normal position of Figs. 6 and 8, and condition the machine for additive actuation. This is accomplished by means of a hook 119 (Figs. 4, 8 and 9) formed at the forward end of the latch 105 which is off-set laterally so that the intermediate portion thereof clears the lug 85 which, however, is disposed in the path of the hook 119. The shaft 78 is thus rocked from the position of Fig. 9 in which it was set by depression of subtraction key 72, to the position shown in Fig. 6. It will be apparent that upon rearward movement of the latch 105, the hook 119 will engage the lug 85 and rock the shaft 78 in a counter-clockwise direction from its position of Fig. 9 to its position of Fig. 8. Such rocking of the shaft 78 pulls link 76 to the left and rocks the walking-beam lever 74 from the position of Fig. 5 to the normal position shown in Fig. 2, where it is maintained by engagement of the stud 82 of arm 79 in the upper notch 83 in plate 77.

The shaft 78 having been rocked to the position shown in Fig. 2, the shoulder 83 of arm 87 is out of the path of the lower portion of the vertical lever 95 in its position of Fig. 6. Other means, therefore, are provided for rocking the levers 89 in all other orders to the left, or higher denominational orders, to release the latches 102 therein to allow the hooks 113 of latches 105 to enter the path of the pins 114 on the associated guide members 60. In addition to performing the function of imparting motion to the parallel motion device of the next higher denominational order through link 55 thereof, the lever 107, in all higher denominational orders or all columns to the left of that in which the key 24 representing the first figure of the subtrahend has been depressed, also serves to release the double-hooked latch 105 from its latch 102 and allow hook 113 to enter the path of the pin 114 of the guide member 60, for the purpose already described. A pin 121 mounted on the lower extremity of lever 107 (Fig. 8) is adapted to engage an upright finger 122 formed on the lever 89 (Figs. 4 and 6) of the next higher denominational order and swing the lever 89 counter-

clockwise from its position of Fig. 6 against the tension of spring 82, as the lever 107 of the lower order is swung on its pivot by reason of the engagement of hook 113 with pin 114. Movement of each lever 89 serves in turn, through its arm 99, to release the associated latch 102 from shelf 104 on lever 105, allowing hook 113 to engage stud 114 and be moved rearwardly thereby, when link 59 is pulled rearwardly by engagement of hook member 58 and toothed wheel 65. The action just described is successively repeated in all higher denominational orders or columns to the left of that in which the first figure of the subtrahend is introduced.

After the double-hooked latches 105 in such higher denominational orders have performed their functions as described, it is necessary that the hooks 113 be disengaged from the studs 114 when the hook members 58 are released from toothed wheels 65 after "9's" have been added into the accumulator. As the lower end of each lever 107 is pulled rearwardly, shelf 104 of the associated lever 105 rides under the shoulder 103 on latch 102, so that during the return movement of lever 107 under contraction of spring 109, the hook 113 is moved downward out of the path of pin 114 against further engagement therewith until shaft 78 is again set for subtraction by depression of key 12. As the lever 107 is thus swung counter-clockwise in its return movement from its position of Fig. 9 to its position of Fig. 8, the pin 121 rides away from arm 122 of lever 89 and allows the lever 89 to return to its normal position under contraction of spring 82. Consequently, all of the subtraction mechanism is returned to inoperative position and the machine is automatically reconditioned for additive actuation.

In machines of the type in which the present invention is embodied, there is usually provided an "overflow" numeral wheel 123 (Fig. 1) to which is transferred the carry of the tens resulting from depression of keys 24 in the last or highest denominational order. Actuating mechanism may or may not be provided in this order, but as it serves no real purpose, it may be omitted. It is apparent, therefore, that if the carry of the tens was allowed to take place in a subtractive operation in the manner hereinbefore described, and "9" could not be added into this order, the numeral wheel 123 would not be returned to zero as in the other orders in which actuating mechanism is provided. Therefore, in the embodiment disclosed in the drawings, it is desirable that the carry be foiled to this overflow numeral wheel 123 when subtraction is being performed. This is accomplished by means of a subtraction or carry cut-out lever 124 (Figs. 2 and 10) which is pivotally supported upon a transverse shaft 125. The lower end portion 126 of the carry cut-out lever 124 curves forwardly and terminates in a tail which engages under a lateral extension 127 on the forward end of the carrying pawl 41. In the normal position of the parts shown in Fig. 2, this forwardly extending tail portion 126 of the lever 124 will not interfere with the rearward and upward movement of the carrying pawl 41 in the usual swinging of the carrying lever 39 to impart a carrying impulse to the lantern wheel and accumulator gear 28.

In order to prevent a carrying impulse from being given to the gear 28 of the overflow numeral wheel 123, however, it is only necessary to swing the carry cut-out lever 124 in a counter-clockwise direction for a very short distance from

its normal or inoperative position of Fig. 2 to its operative position of Fig. 5. In the latter position, the upper surface of the forwardly extending tail portion 126 of the lever 124 contacts the lateral extension 127 and lifts the forward end of the carrying-pawl 41 to swing the latter in a counter-clockwise direction into inoperative position, where it is adapted to be held until released by the rearward motion of the carrying transfer lever 39 in a foiled carrying operation.

In order to accomplish this result, the carry cut-out lever 124 functions to cause the carrying pawl 41 to be latched in inoperative or carry foiling position during the rearward swing of the carrying lever and to be unlatched after an attempted carry has been foiled. To this end a link 128 is pivotally secured at one end to an upright arm 129 provided on the lever 107 in the highest denominational order and at the other end to the carry cut-out lever at 131 (Figs. 2 and 10). It will be apparent that clockwise motion of the lever 107 resulting from engagement of the hook 113 with the pin 114 of the guide member 60, as previously described, will, through the link 128, cause the carry cut-out lever 124 to engage the lateral extension 127 on the forward end of the carrying pawl 41. This engagement rocks the rearward end of the carrying pawl downward, and engages a lateral extension 132 thereon under a shoulder 133 provided on a latch 134 pivotally mounted on the carry transfer lever 39, as shown in Fig. 10. The latch 134 is held in engagement with the lateral extension 132 of the carrying pawl 41 by means of a spring 135. Consequently, subsequent rearward movement of the upper end of the carrying pawl 41 will be below the pins of the lantern wheel 28, and the carry attempted by such movement of the carrying pawl will be foiled.

As has been mentioned, rearward swing of the carrying lever 39 in an attempted carrying operation is utilized to release the latch 134 and allow the carrying pawl 41 to return to its normal position of Fig. 2. This is accomplished by means of a stud 136 (Fig. 2) provided on the carry cut-out lever 124 and disposed in the path of a lower extension 137 of the latch 134. As the carrying lever 39 swings rearward in the carrying operation earlier described, the lower extension 137 of the latch 134 will contact the stud 136 mounted on the carry cut-out lever 124 and, as the carrying lever continues its rearward movement, the lateral extension 132 will ride from under the shoulder 133 on the latch 134 to allow the rearward end of the carrying pawl 41 to rise to its normal or active position of Fig. 2. The carry cut-out lever 124 will, of course, have been returned to its normal inoperative position of Fig. 2 by counter-clockwise movement of lever 107 under contraction of spring 109.

It is thought that the invention and its attendant advantages will be understood from the foregoing description, and it will be apparent that various changes may be made in the form, construction and arrangement of the parts without departing from the spirit and scope of the invention or sacrificing all of its material advantages, the form hereinbefore described and illustrated in the drawings being merely a preferred embodiment thereof.

I claim as my invention:

1. In a calculating machine, an accumulator, denominational orders of mechanism for actuating said accumulator, denominational orders of keys for digitally controlling said actuating mech-

anisms, and settable mechanism operable in response to the operation of any said digital control key for initiating the operation of said actuating mechanisms in all denominational orders higher than that of said key.

2. In a calculating machine having an accumulator, denominational orders of mechanism for actuating said accumulator, and keys for controlling said actuating mechanisms; means settable to condition the machine for subtraction, and means operable in response to the setting of said settable means and the subsequent operation of any said control key for initiating the operation of the actuating mechanisms in all denominational orders higher than that of said operated key to register 9's in said accumulator.

3. In a calculating machine having an accumulator, denominational orders of mechanism for actuating said accumulator, and keys for controlling said actuating mechanisms; normally inoperative means conditionable for actuation in response to the operation of any said control key for initiating the operation of said actuating mechanisms in all denominational orders higher than that of said operated key, and means for returning said first mentioned means to inoperative position.

4. In a calculating machine having an accumulator, denominational orders of mechanism for actuating said accumulator, and a plurality of denominational orders of keys, each of said orders being associated with one of said orders of actuating mechanism to initiate and control operation thereof; additional means for initiating operation of each of said orders of actuating mechanisms and means operable in response to the depression of any said key for initiating operation of said operation initiating means in all denominational orders higher than that of said depressed key.

5. In a calculating machine having an accumulator, denominational orders of mechanism for actuating said accumulator, and columns of depressible keys for controlling operation of said actuating mechanisms; means settable to condition the machine for subtraction, and means conditioned by said settable means and operable in response to the depression of any said key and by the actuating mechanism associated therewith to cause operation of the next higher denominational order of actuating mechanism.

6. In a calculating machine having an accumulator, denominational orders of mechanism for actuating said accumulator, and depressible keys for controlling operation of said actuating mechanisms; means settable to condition the machine for subtraction, means conditionable by said first means for operation by depression of any said key, and means conditioned by said conditionable means for operation by the actuating mechanism associated with said depressed key to effect operation of the next higher denominational order of actuating mechanism.

7. In a calculating machine having an accumulator, denominational orders of mechanism for actuating said accumulator, and depressible keys for controlling operation of said actuating mechanism; normally inoperative means settable to condition the machine for subtractive operation, and means conditioned by said settable means and operable in response to the depression of any said key to successively and automatically effect operation of said actuating mechanisms in all denominational orders higher than that of said depressed key.

8. In a calculating machine having an accumulator, denominational orders of mechanism for actuating said accumulator, and depressible keys for controlling operation of said actuating mechanism; normally inoperative means settable to condition the machine for subtractive operation, means conditioned by said settable means and operable in response to the depression of any said key to successively and automatically effect operation of said actuating mechanisms in all denominational orders higher than that of said depressed key, and means operable upon operation of said conditioned means to recondition the machine for additive actuation.

9. In a key-responsive calculating machine having denominational columns of depressible keys, an accumulator, denominational orders of mechanism for actuating said accumulator, means for determining differential operation of said actuating mechanism in accordance with the digital value of the key depressed, manually settable control mechanism, and mechanism operable under control of said settable mechanism in response to the depression of a said key for initiating the operation of said actuating mechanism independently of said differential means to add 9's in all denominational orders of the accumulator higher than that of the key depressed.

10. In a calculating machine, an accumulator, denominational orders of actuators for said accumulator, means for driving said actuators, power means, means for connecting said power means and said driving means, keys for effecting said connection and for controlling the digital actuation of said actuators, manually settable control mechanism, and mechanism conditioned for operation by said settable mechanism and initially operated by depressing any said control key for automatically connecting said power means and said driving means in all denominational orders higher than that of said depressed key.

11. In a calculating machine, an accumulator, denominational orders of actuators for said accumulator, means for driving said actuators, power means, means for connecting said power means and said driving means, keys for effecting said connection and for controlling the digital actuation of said actuators, manually settable control means, and mechanism operated under control of said settable means in response to the operation of any said key to successively and automatically connect said power means and said driving means in all denominational orders higher than that of said operated key.

12. In a calculating machine, an accumulator, denominational orders of actuators for said accumulator, means for driving said actuators, power means, means for connecting said power means and said driving means, keys for effecting operation of said connecting means and for controlling the digital actuation of said actuators, settable control means, and mechanism operated by the connection between said driving means and said power means in response to the setting of said control means followed by operation of any said key to effect connection in the next higher denominational order between the power means and driving means.

13. In a calculating machine having an accumulator, denominational orders of actuators for said accumulator, means for driving said actuators, power means, means for connecting said power means and said driving means, and keys

for effecting operation of said connection and for controlling the digital actuation of said actuators; a subtraction control device, and means conditionable by said control device for effecting operation of said connecting means upon operation of any said key, to effect connection between said power means and said driving means in all denominational orders higher than that of said key.

14. In a power driven, key-responsive calculating machine having an accumulator, denominational orders of actuating mechanism therefor, driving mechanism for the said actuating mechanism, power means, means for connecting said power means and said driving mechanism, and ordinal keys for controlling the connection between said driving mechanism and said power means; a subtraction control device, means conditioned by said device to effect operation of said connecting means in response to the operation of any said key, so as to automatically and successively connect the said driving mechanism and said power means in all denominational orders higher than that of said key, and means for returning said subtraction control device and associated connecting means to normal ineffective position.

15. In a power-driven, key-responsive calculating machine having an accumulator, denominational orders of actuating mechanism therefor, driving mechanism for said actuating mechanism, power means, means for connecting said power means and said driving mechanism, and ordinal keys for controlling the connection between said driving mechanism and said power means; other means operative upon depression of any ordinal key to successively and automatically effect connection between said driving mechanism and said power means to add 9's in all denominational orders higher than that of said key, and selectively operable means for making said connecting means operative or inoperative.

16. In a power-driven, key-responsive calculating machine having an accumulating, denominational orders of actuating mechanism for said accumulator, means for driving said actuating mechanism, power means, means for connecting said driving means and said power means, and columns of depressible keys for effecting said connection and for controlling the digital degree of actuation of said actuating mechanism; a device selectively settable to condition the machine for subtractive operation, means conditioned by said device and operable upon depression of any said key for effecting operation of said connecting means to cause said actuating mechanism to add 9's in all denominational orders of said accumulator higher than that of said depressed key, and means operable upon operation of said last mentioned means to condition the machine for additive operation.

17. In a calculating machine having an accumulator including tens transfer mechanisms and an overflow numeral wheel, denominational orders of actuating mechanism for said accumulator, and keys for controlling the operation of said actuating mechanisms; means operable in response to the operation of any said control key for initiating operation of said actuating mechanism to add 9's in all denominational orders of said accumulator higher than that of said operated key, and means operated by the operation initiating means in the highest denominational order in adding 9, for preventing operation

of the tens transfer mechanism associated with said overflow numeral wheel.

18. In a calculating machine having a series of denominational orders of accumulator mechanism including tens transfer mechanism and an overflow numeral wheel, actuating mechanism for each order of said accumulator mechanism except said overflow numeral wheel, and depressible keys for controlling operation of said actuating mechanism; means settable to condition the machine for subtraction, means conditioned by said settable means and operable in response to the depression of any said control key for initiating operation of said actuating mechanism to add 9's in all orders of said accumulator higher than that of said depressed key, and means operated by said operation initiating means in the highest denominational order for disabling the tens transfer mechanism associated with said overflow numeral wheel when said machine is set for subtraction.

19. In a power driven calculating machine the combination of a multiple order accumulator, an actuating mechanism for each denominational order including a key responsive power trip device adapted when operated to initiate an adding cycle, a power actuated member movable in such cycle, a subtraction control device, a motion transmitting device for each denominational order including an element shiftable from a normally inactive position into driving relation with the power actuated member of one order and operatively associated with the trip device of the next higher order, means operating under the joint control of said subtraction control device and the trip device of one order to shift said element into its active position, and means operable as an incident to the shifting movement of said element in any one order to cause a corresponding shift of the element in the next higher order.

20. In a power driven calculating machine, the combination of a multiple order accumulator, an actuating mechanism for each denominational order, including a key-responsive power trip device adapted when operated to initiate an adding cycle, a power actuated member movable in such cycle, a subtraction control device, a normally ineffective connection between the power actuated member of one order and the trip device of the next higher order, and means operable under the joint control of said subtraction control device and of the trip device of one order to render said connection effective to actuate the trip device of the next higher order.

21. In a power driven calculating machine the combination of a multiple order accumulator, an actuating mechanism for each denominational order including a key-responsive power trip device adapted when operated to initiate an adding cycle, a power actuated member movable in such cycle, a subtraction control device, means including an element shiftable into and out of driving relation with the power actuated member of one order and operatively associated with the trip device of the next higher order, and means including a subtraction control device common to all of said orders for shifting said element from an inactive position to an active position to establish a connection between the power actuated member of one order and the trip device of the next higher order.
